UNITED STATES PATENT OFFICE.

JAMES HARRISON, OF NEW YORK, N. Y.

IMPROVEMENT IN SIGNS.

Specification forming part of Letters Patent No. 141,788, dated August 12, 1873; application filed July 1, 1873.

To all whom it may concern:

Be it known that I, JAMES HARRISON, of the city, county, and State of New York, have invented a new and useful Improvement in Signs; and I do hereby declare the following to be a full, clear, and exact description thereof, which will enable those skilled in the art to make and use the same, reference being had to the accompanying drawing forming part of this specification, in which drawing—

Figure 1 is a front view of a sign constructed according to my invention. Fig. 2 is a transverse central section of the same.

Similar letters indicate corresponding parts.

This invention consists in a sign made of glass or other transparent material, the body or ground of which is rendered opaque by painting or otherwise upon its rear or unexposed surface, while the raised letters or figures of the same are left transparent, and are ornamented by means of knobs, buttons, or other suitable ornaments, which are arranged on the surface thereof in such a manner that said letters or figures appear in bold relief, and by these means a highly ornamental and useful sign is produced at a small cost.

In the drawing, the letters A A designate two parts or sections of my sign, which is made of glass or other transparent material, and on said parts are formed the letters or characters B B, which are in relief, being made to project above the surface thereof; and on

said characters I arrange a series of protuberances or ornaments, a a, which serve to embellish and impart a fine appearance to the same. The parts or sections A A are joined together by means of a shoulder, C, sunken on the edge of one part, which receives and supports the free edge of the next part; and by these means the sign receives a smooth or even surface. The body or ground of my sign is obscured by means of a layer, b, of paint or other material of an opaque nature, which is applied on its rear or unexposed surface when a glass ground is used, omitting the letters or characters B, which are left transparent; and by these means and by means of the knobs or buttons or ornaments a a said letters are rendered very distinct and ornamental.

What I claim as new, and desire to secure by Letters Patent, is—

The letters or figures of a sign made of a transparent material, with the protuberances a a, with or without the shoulder C, the ground portion of said letters or figures being covered with the material b, substantially as herein shown, for the purpose specified.

This specification signed by me this 26th day of June, 1873.

JAMES HARRISON.
